2 SHEETS--SHEET 2.

UNITED STATES PATENT OFFICE.

JOSEPH HUNTER DICKINSON, OF LARCHMONT, NEW YORK, ASSIGNOR TO THE
AEOLIAN COMPANY, A CORPORATION OF CONNECTICUT.

AUTOMATIC MUSICAL INSTRUMENT.

Application filed November 5, 1918. Serial No. 261,239.

To all whom it may concern:

Be it known that I, JOSEPH HUNTER DICKINSON, a citizen of the United States, residing at Larchmont, New York, have 5 invented certain new and useful Improvements in Automatic Musical Instruments, of which the following is a specification.

This invention depends upon the discovery that the average unmusical person playing an automatic piano can readily give a pleasing musical interpretation of the solo notes of the music-roll (1) by listening to the dynamics musical expression given automatically or by a skilled performer to the 15 harmony or accompaniment notes,—and (2) by himself sympathetically operating, as he listens, the means which controls the dynamics of the solo notes. The invention resides in the combination of means by which 20 the above discovery can be practically utilized in a working instrument.

The drawings show diagrammatically in Figs. 1 and 2 two of the possible embodiments my invention is adapted to take, Fig. 25 1 showing the preferred embodiment. The drawings show the parts spread out diagrammatically with only the operative connections between them indicated, but it will be understood that in practice they will ordinarily be compactly embodied in an operative manner in the piano. Also, no attempt has been made to show the parts in their relative size or correct proportions. Fig. 3 is a horizontal section partly in plan 30 on the line 3—3 in Fig. 2 looking in the direction of the arrows, but the valve is shown partly open instead of closed as in Fig. 2.

1 designates the music-sheet of the automatic piano, 2 the usual tracker-bar supposed to have the usual note-playing ducts, 3 the automatic player action supposed to comprise the usual pouches operatively related to the ducts of the tracker-bar, valves, 45 striker-pneumatics and other parts well known in this art. Also, 4 is the usual pair of foot-pedals for operating the usual pair of pumbers 5—5 for exhausting the usual reservoir 6.

50 7 is a regulating or expression bellows operatively connected between the automatic player action 3 and the reservoir 6 to control the degree of air-tension in said action and the dynamics with which the ac-

companiment notes are struck. The diagram shows a well known type of said bellows wherein 7^a is a box having sides and a top with a port through it at 7^b but having no bottom. 8 is an internal port controlled by the knife-valve 9 inside the box 7^a. This 55 port 8 is the mouth of a pipe or coupling which projects inwardly through the rear-side of the box and at its other end is connected by tubing 10 with the reservoir 6. 11 is a rock-shaft projecting through a suitable bearing-opening in the front side of the box. Within the box it has a rigid crank-arm 12 pivotally connected to the heel of the valve 9. Outside the box it has a rigid crank-arm 13. 14 is a rod pivotally 60 connecting said crank-arm 13 with the top board of the so-called accordion bellows 15, consisting of a plurality of separate bellows a, b, c, d, secured together in a stack, one on top of another, the bottom-board of the 65 stack being secured to a fixed support, said separate bellows having different extents of collapse. Tubing 16 and valve-boxes 17 operatively connect in well-known manner the tracker-ducts 2^a, 2^b, 2^c, and 2^d respectively 70 with the separate compartments, a, b, c and d of the accordion bellows. The tension spiral spring 18 keeps the accordion bellows normally expanded as shown. It will be understood that whenever music-sheet perforations 25 register with one or more of the tracker-ducts 2^a to 2^d, the corresponding 75 valves 17 are operated to cause the exhaust and collapse of the corresponding compartments a to d of the accordion bellows. 80

22 is a link connecting the toe of the knife-valve 9 with the movable-board 7^c of the regulating-bellows. 23 is the usual regulating or expression bellows spring connecting the movable board 7^c with a stationary part 24, said spring as usual being an adjustable tension spring tending to open the bellows and also tending by means of the link 22 to swing the toe of the valve 9 downwardly so as to uncover its port 8. 85

19 is a tight box mounted on the box 7^a divided into right- and left-hand compartments by a partition having a port 19^a controlled by a flap-valve 20. 21 is a pipe which connects the player-action 3 with the 90 left-hand compartment of the box 19.

From the foregoing, it will be seen that the player-action 3 is operatively connected

with the suction-reservoir 6 via the pipe 21, port 19^a, port 7^b, expression bellows 7, port 8 and pipe 10.

In addition, a by-pass connection between 5 the player-action 3 and the suction reservoir 6 is provided comprising the following:—A pipe 26 leading from the left-hand compartment of the box 19; the upper compartment 27^a of valve-box 27; port 27^b in 10 the horizontal partition 27^c of said box, controlled by valve 27^d on pouch 27^e; lower compartment 27^f of said box; and pipe 28 leading back to the suction-reservoir 6. The drawing shows said pouch 27^e inflated as 15 if connected with the atmosphere with the valve 27^d closed on its port. When said pouch 27^e is exhausted, the valve 27^d opens and a direct connection is established between the player-action and the suction-reservoir 6 via the pipe 26, port 27^b and pipe 28. It will be understood that whenever this direct connection is made, the active striker pneumatics in the player-action 3 are exhausted by the direct suction from 20 the reservoir 6, and sound their notes more loudly than when said pneumatics are exhausted via the regulating bellows 7.

The opening of the aforesaid valve 27^d is automatically controlled from music-sheet perforations 29 registering with a 30 tracker-duct 30 connected by a tube 31 with a pouch 32^a in a valve-box 32. This pouch operates an "inside" valve 32^b working between an upper port 32^c to the atmosphere 35 and a lower port 32^d connecting with the exhaust in the lower compartment 32^e of the valve-box. 32^f is a bleed; and 32^g is a tube connecting the upper compartment of the valve-box with the pouch 27^e. From the 40 foregoing it will be seen that when the solid part of the music-sheet covers the tracker-duct 30, the pouch 32^a, exhausted through the bleed 32^f, will be deflated with the valve 32^d closed on the exhaust port 32^d, and with the atmosphere port 32^c open, thereby admitting atmosphere to and inflating the pouch 27^e to close the valve 27^d on its port 27^e. Vice versa, whenever a music-sheet perforation 29 opens the tracker-duct 30, 45 the valve 32^b in valve-box 32 is lifted and connects the exhaust in 32^e with the pouch 27^e, thereby deflating it and lowering the valve 27^d from its port 27^e. In short, whenever and as long as one of the music-perforations 29 registers with the tracker-duct 30, the described direct by-pass connection 50 26—28 is made between the player-action 3 and the suction reservoir 6. Otherwise, the connection is an indirect one by way of 55 the expression bellows 7.

In the illustrated music-sheet, 33 designates the harmony or accompaniment note-sounding perforations; and 34 the solo note-sounding perforations. The perforations 25 60 are related to the former and in practice

will represent a musically correct interpretation of the loud and soft shading or dynamics of said harmony or accompaniment. Further, said perforations 25 will automatically produce said correct interpretation by collapsing the accordion bellows to varying extents depending on the number and position of the perforations. As each perforation or group of perforations 25 register with their tracker-ducts, the accordion bellows will correspondingly shift the heel of the knife-valve 9 relative to its port; and this in turn will correspondingly vary the degree of suction in the player-action, as will be well understood by those skilled in the art. The perforations 29, as heretofore explained, automatically effect a direct connection between the player action and the suction reservoir; said perforations being located at or a little ahead of the respective solo-note perforations to which they belong. Further, the front ends of the solo note-perforations 34 are out of line with those of the accompaniment note-perforations 33, preferably retarded; and hence the dynamics of the accompaniment notes will be controlled by the perforations 25 independently of the solo notes, and the dynamics of the solo notes will be controlled by the perforations 29 independently of the accompaniment notes.

In practice, the described instrument operates as follows:—The music-roll having been inserted, the operator plays the instrument by pumping the pedals. As the music-sheet travels across the tracker-bar, the music-perforations 33 and the related dynamics perforations 25 cause the harmony or accompaniment notes to be sounded with an expressive, musically rendition of their dynamics,—accomplishing this automatically, as already explained, through the accordion bellows 15 acting on the knife-valve 9 of the expression bellows 7. Thus, the operator by merely pumping the instrument without the exercise of any musical skill, automatically renders the fundamental, harmony part of the composition. Hearing this expressive rendition, it is natural and easy for him to pump sympathetically with it. As the volume of tone swells out louder, he pumps harder; and when the expression is delicate, pumps gently, and so on through all the indescribable gradations in effects. The apparatus is such that this constantly provides a degree of suction in the reservoir 6 for playing the solo notes 34 as compared with that in the expression bellows 7 for playing the harmony notes 33, which is neither too high nor too low, but which is a relatively or proportionally sufficiently higher suction to sound the solo notes 34 eloquently louder than the then sounding harmony. The described sheet-perforations 29 by operating the valve 27^d automatically release this suc- 130

tion from the reservoir 6 so as to affect the solo notes 34 without affecting the adjacent out-of-alignment harmony notes 33.

By my invention, it is surprising how easily and satisfactorily the operator can expressively render the solo and most expressive parts of any musical composition. On the other hand, without the automatically expressed harmony as a guide, and without the means for utilizing it in the production of the solo, the unmusical operator is continually musically lost and unable to render either solo or harmony with eloquence or charm, whereas, as stated, this becomes readily practical to the same person playing an instrument embodying my invention.

Although I prefer the foregoing, the automatic operation of the valve 27^a by the side-perforations 29 can be dispensed with; 20 and a manually operated valve 35 can be substituted as in Fig. 2 for said valve 27^a and the automatic means for operating it. This valve 35 is shown as a slide valve controlling a V-shaped port 36 in the partition 25 37 of the box 38 connected between the upper tube 23 and lower tube 28. The hand lever 39 connects with the valve 35 so that the port 36 can be momentarily opened wide and then closed in accordance with the occurrence at the tracker-bar of the forward ends 30 of the respective solo notes 34 recognizable in the music-sheet by their differentiated appearance or otherwise.

If it should be necessary or desirable to substitute an electric or power-driven exhauster 40 as in Fig. 2 for the preferred foot-driven exhauster in Fig. 1, then the aforesaid hand valve 35 will be not only momentarily opened as before described, but 40 will be opened by the operator to varying extents proportionally to the degree of loudness with which he then hears the harmony notes being automatically expressed.

It will be understood that otherwise the 45 devices illustrated in Fig. 2 are the same as those in Fig. 1 and consequently they have not been set forth with the same detail as in Fig. 1, but like numerals have been used to designate like parts.

50 Of course, a reversal is conceivable wherein the dynamics of the solo are automatically expressed, leaving it to the operator to express the dynamics of the harmony notes in accordance with this invention. Also, other 55 changes and modifications are doubtless possible which are nevertheless within the spirit of my invention and of the foregoing disclosure and the annexed claims, and as such covered thereby.

60 What I claim is:—

1. In combination with a musical instrument, a music-sheet controlled player action, a tracker-board, a music-sheet having sets of note perforations for the solo and harmony 65 parts respectively of a composition, the per-

forations of one set being advanced relatively to those of the other set and having dynamics-expression perforations related to the note perforations for the harmony part of the composition, a foot-pumped air tension producer for said action, means operatively related to said action and producer and controlled from said dynamics-expression perforations to vary the air tension in the action to give music-sheet controlled dynamics-expression to the notes of the harmony part of the composition which will constitute an aural guide to the performer in the rendition of the solo part of the composition, said means being operative to 70 maintain a substantially less powerful air tension in the action than in the producer, and means adapted to connect said producer with the player action at the times when the solo note perforations reach the tracker-board to produce under the control of the performer a relatively higher air tension in the action, thereby giving to the notes of the solo part of the composition dynamics-expression which is distinctively louder than 75 that given to the notes of the harmony part by the dynamics-expression perforations of the note sheet.

2. In combination with a musical instrument, a music-sheet controlled player-action 80 including a tracker-board; a music-sheet having dynamics-expression perforations related to one of a plurality of musical parts represented by music-perforations in said sheet; an air-tension producer operatively 85 connected with said action; means controlled from said expression-perforations for varying the air-tension in the action to sound the first-named musical part with music-sheet controlled dynamics-expression; and 90 means controllable by the operator and operable to produce an air tension in the player action which is proportionally different from that produced by the aforesaid music-sheet controlled means at the times when the respective music-perforations for said second 95 part reach the tracker-board, thereby giving relatively different dynamics-expression to said second part.

3. In a musical instrument adapted to be 100 played from a music-sheet, the combination of a player action controlled by the music-sheet, music-sheet controlled means for causing the player action to render one musical part of the composition with dynamics-expression which will constitute an aural guide to the performer in the rendition of the other musical part of the composition, and means controllable by the performer and capable of giving dynamics-expression to said 105 other part of the composition as indicated by said aural guide.

4. In a musical instrument adapted to be 110 played from a music-sheet having note perforations for the solo and harmony parts of 115

70

5 a composition and also dynamics-expression perforations operatively related to the note perforations for one of said parts of the composition, the combination of a player action controlled by the solo and harmony note perforations of the music-sheet, means controlled by the dynamics-expression perforations of the music-sheet to give dynamics-expression to the corresponding part of the 10 composition and to thus produce an aural guide for the performer in rendering the other part of the composition, and means controllable by the performer and related to the note perforations for said other part 15 only of the composition for giving, at the will of the performer, dynamics-expression to said other part of the composition.

5. In a musical instrument, the combination of a music sheet having solo and 20 harmony note perforations and dynamics-expression perforations related to the harmony note perforations, a player action controlled by the solo and harmony note perforations of the music sheet, means controlled by said dynamics-expression perforations to give dynamics-expression to the 25 harmony part of the composition and thus produce an aural guide which will indicate to the performer the dynamics-expression to be given to the solo part of the composition, and means controllable by the performer and related to the solo note perforations only 30 of the music-sheet for giving, at the will of the performer, dynamics-expression to the solo part of the composition, as indicated by said aural guide.

6. In a musical instrument adapted to play a music-sheet having solo and harmony note perforations and also dynamics-expression perforations related to the harmony note perforations, the combination of a 40 player action, an air-tension producer connected thereto, means controlled by the dynamics-expression perforations for regulating the air tension in the player action

for the playing of the harmony notes and to thus render the harmony with dynamics-expression which constitutes an aural guide to the performer in the rendition of the solo, and means controllable by the performer for 50 producing a relatively increased air tension in the player action for the playing of the solo notes only, as indicated by said aural guide.

7. In a musical instrument, the combination of a music-sheet having note perforations for the solo and harmony notes of a composition, the note perforations for the respective parts of the composition being differently arranged thereon, and also having dynamics-expression perforations for one of said parts of the composition, a cooperative tracker board, a player action controlled by the solo and harmony note perforations of the music-sheet, an air-tension producer connected to the player action, means controlled by said dynamics-expression perforations for regulating the air tension in the player action, thus expressing the dynamics of the part of the composition corresponding to the note perforations to which the dynamics-expression perforations are related and thereby providing an aural guide for the performer to follow in the rendition of the other part of the composition, and means controllable by the performer for producing relatively increased air tension in the player action at the times when the note perforations for said other part only of the composition, come into register with the tracker board, thus giving, at 70 the will of the performer, a distinctive dynamics-expression to said other part only of the composition, as indicated by said aural guide.

In testimony whereof, I have signed my name to this specification this 4th day of November, 1918.

JOSEPH HUNTER DICKINSON.
